UNITED STATES PATENT OFFICE

REUBEN GEORGE BREWER, OF VANCOUVER, WASHINGTON

DESIGN FOR A WINDOW DISPLAY FIXTURE

Application filed May 16, 1931. Serial No. 39,874. Term of patent 3½ years.

To all whom it may concern:

Be it known that I, REUBEN GEORGE BREWER, a citizen of the United States, and a resident of the city of Vancouver, county of Clarke, State of Washington, have invented a new, original, and ornamental Design for a Window Display Fixture, of which the following is a specification, reference being had to the accompanying drawings, forming part thereof, and in which

Figure 1 is a perspective view of the window display fixture, and Figure 2 is a transverse vertical section through the central portion of Figure 1 and looking toward the right thereof.

I claim:

The ornamental design for a window display fixture, as shown.

REUBEN GEORGE BREWER.
